UNITED STATES PATENT OFFICE.

HUGH DOWNS, OF PITTSBURG, AND WILLIAM C. WALLY, OF ETNA,
PENNSYLVANIA.

WIRE-ROPE PROTECTOR.

No. 812,413.

Specification of Letters Patent.

Patented Feb. 13, 1906.

Application filed June 27, 1905. Serial No. 267,186.

To all whom it may concern:

Be it known that we, HUGH DOWNS, residing at Pittsburg, and WILLIAM C. WALLY, residing at Etna, in the county of Allegheny and State of Pennsylvania, citizens of the United States, have invented certain new and useful Improvements in Wire-Rope Protectors; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to a new, novel, and useful improvement in a device to be attached to a wire cable used in oil, gas, and water well-drilling for the purpose of protecting said cable against wearing by whipping against the sides of the tubing or hole during the process of drilling.

This device may be termed a "guard" or "protector," as it serves to preserve the wire cable during the process of drilling, and thus materially lessens the chances of the cable being broken in two and the drilling-tools being dropped into the hole, thus necessitating any expensive fishing operation.

Our device has for its object, along with that described above, the combination and arrangement of parts whereby it can be produced at a minimum cost and when in operation can be quickly and readily adjusted on and off the cable.

In the accompanying drawings, forming a part of this specification, we have shown several views of our invention.

Figure 1 is a front elevation as attached to a section of cable. Fig. 2 is a vertical sectional view taken on line 2 2 of Fig. 1. Fig. 3 is a cross-section on line 3 3 of Fig. 2. Fig. 4 is a side and edge view of the wedge-slip used in connection with our device.

Throughout the several views the numeral 1 designates the body portion of our device. This portion is made of any hard metallic substance and in actual use will be about eighteen inches in length by about four and one-half inches in diameter, or it may vary according to the size of casing used. Running the full length of this body portion is a double-tapered slot 2, being slightly wider at the top than bottom. The rear wall of this

slot is corrugated to conform to the twist of the cable and affords a seat for the same. Adapted to slip into the slot 2 through the top of the member 1 is a double-tapered wedge 3, constructed to conform to the taper of the slot and the thickness of the member 1, so that when firmly seated in said slot the outer edge of this wedge will be flush with the face of the member 1. Formed in the inner edge of this wedge is a groove 4, running the entire length of the same, which affords a seat for the cable when in position. Also formed integral with the wedge at the top is a projection 5, having an eye formed therein, which affords a means of lifting the wedge out of its seat. A plurality of notches 6 are also formed in the outer edge of this wedge as a means of starting the same out of its seat or of more firmly driving it down on the taper.

Formed through the side of the member 1 is a tapered slot 7 to receive the correspondingly-tapered key 8. This key also passes through a slot 9, formed through the wedge 3, and constitutes a means of securely locking the wedge in its seat. Sufficient play is allowed through the slot 9 in order that when the key 8 is driven through the wedge 3 it will force the same downward into its seat.

The operation for putting on and removing our device consists simply in laying the cable in the slot 2, driving the wedge 3 into its seat, and then inserting the locking-key 8. In this position it will be next to impossible for the protector to jar loose from the cable and by so doing drop into the hole on top of the drilling-tools. To release the device, simply knock out the key 8 and lift the wedge out of its seat. When in position on the cable during the drilling process, our device will serve to center the cable in the casing and prevent the rope from whipping the sides of the hole at every downward stroke. The number of our devices necessary to protect the wire cable will depend on the depth of the hole; but in ordinary cases two or three will be ample.

Having thus fully shown and described our invention, what we claim, and desire to secure by Letter Patent, is—

1. In a wire-rope protector of the character described, a body portion having a double-tapered slot extending the full length thereof and adapted to fit over the cable; a

- double-tapered wedge to conform to the tapered slot adapted to fit in the latter, and means for locking said wedge in its seat; as, and for, the purpose set forth. 35
5. 2. In a wire-rope protector of the character described, a body portion having a double-tapered slot extending the full length thereof, and adapted to fit over the cable; a double-tapered removable wedge to conform 40 to the tapered slot adapted to fit in the latter; and a tapered locking-key to fit in an opening formed through the side of the body portion and through said wedge; as, and for, the purpose set forth.
15. 3. In a wire-rope protector of the character described, a body portion having a double-tapered slot extending the full length thereof, and adapted to fit over the cable; a double-tapered removable wedge to conform 45 to the tapered slot, adapted to fit in the latter; a tapered locking-key to fit in an opening formed through the side of the body portion and through said wedge; and means whereby the wedge may be removed; as, and for, the purpose set forth.
25. 4. In a wire-rope protector of the character described, a body portion having a double-tapered slot extending the full length thereof, and adapted to fit over the cable; corrugations formed in the rear wall of said slot; a double-tapered removable wedge to conform 50 to the tapered slot, adapted to fit in the latter; a groove formed in the inner edge of said wedge; a tapered locking-key to fit in an opening formed through the side of the body portion and through said wedge; and means whereby the wedge may be removed; as, and for, the purpose set forth.
30. 5. In a device of the character described, a body portion having a groove to receive a cable, and a filler for the groove binding against the cable and means for holding the filler against displacement. 55
6. In a device of the character described, a body portion having a groove to receive a cable, and a filler for the groove binding against the cable and means extending transversely of the body for holding the filler against displacement.
7. In a device of the character described, a body having a wedge-slot, adapted to receive a cable and a wedge fitting within said slot and bearing against said slot and said wedge having notches on its outer surface. 60
8. In a device of the character described, a body having a wedge-slot adapted to receive a cable, and a wedge fitting within said slot and bearing against the cable, and an eye carried by the wedge.

In testimony whereof we affix our signatures in presence of two witnesses.

HUGH DOWNS.

WILLIAM C. WALLY.
